UNITED STATES PATENT OFFICE.

JOSEPH GRULLER, OF HOUSTON, TEXAS.

SCRAPER-SETTING TOOL.

Application filed March 30, 1925. Serial No. 19,458.

This invention relates to new and useful improvements in a scraper setting tool.

One object of this invention is to provide an implement of the character described especially designed for use in sharpening wood scrapers such as are used by carpenters and cabinet makers for the purpose of smoothing the surface of the work.

Another object of the invention is to provide an implement of the character described which is readily adjustable to scrapers of different thicknesses.

A further feature of the invention is to provide a device of the character described which is of simple and practical construction which may be cheaply and easily produced by the use of which the scraper may be quickly and easily sharpened.

With the above and other objects in view this invention has particular relation to certain novel features of construction, operation and arrangement of parts, an example of which is given in this specification and illustrated in the accompanying drawings, wherein:—

Figure 1 shows a longitudinal sectional view of the implement.

Figure 2 shows a side view thereof.

Figure 3 shows a fragmentary plan view thereof.

Figure 4 shows an enlarged fragmentary edge view of the scraper, showing the sharpening operation completed, and

Figure 5 shows an enlarged fragmentary edge view thereof showing the same completely sharpened.

Referring now more particularly to the drawings, wherein like numerals of reference designate similar parts in each of the figures the numeral 1 designates a hand grip, having the end chucks 2, 2, and whose ends are protected by the metal end ferrules 3, 3.

Shanks 4 and 5 are provided, whose inner ends 6 and 7, respectively, are tapered and fitted into the respective chucks 2, 2.

The shank 4 has its outer end forked, forming the diverging fingers 8, 8 whose outer ends are pointed. The scraper 9, used for scraping and smoothing purposes by carpenters and cabinet makers is a flat rectangular blade, formed of steel, or similar metal. This blade is run over the surface to be smoothed by hand, with the corners of either side or end forming the scraping edge, as 10. These corners soon become

rounded off or dull, so that they will not properly do the work and must be sharpened, or set.

The shank 5 has the diverging studs 11, 11, at its free end forming an obtuse angle between them.

The numerals 12, 12 designate opposing segments which are spaced apart and are formed with the shanks 13, 13. A cross pin 14' is fixed to the shank 5 and its ends project through aligned holes in the shanks 1 and are outwardly threaded to receive the clamp nuts 14, 15 which clamp the respective shanks to the pin 14'. The segments 12 have openings, or bearings through which the studs 11 extend. If desired the inside nuts may be dispensed with and the coil springs 15' substituted for them, as shown in Figure 3.

In order to sharpen the scraper its edges are run back and forth between the diverging fingers 8, as indicated in dotted lines in Figure 1, and this operation will upset or overturn the corners, as indicated, in an exaggerated form, in Figure 4. The scraper is then placed between the segments, or guides 12, as indicated in dotted lines in Figure 1, with the corners, to be sharpened bearing against the respective diverging studs 11, and the scraper is then moved back and forth until the said corners are sharpened, said corners being thrown out and formed into scraping edges, as 10, indicated in an exaggerated form in Figure 5, and the sharpening operation is thus completed.

The segments may be adjusted toward or from each other in an obvious manner to accommodate scrapers of different thicknesses.

What I claim is:—

1. A scraper setting tool including a shank, a grip carried thereby, one end of the shank having diverging friction members, and spaced guides carried by said end of said shank.

2. A scraper setting tool including a shank, a grip carried thereby, one end of the shank having diverging friction members, and spaced guides carried by said end of said shank, said guides being adjustable toward or from each other.

3. An implement of the character described including a grip, shanks secured thereto and projecting therefrom the outer ends of said shanks being formed with diverging friction members to receive a scraping blade between them.

4. An implement of the character described including a grip, shanks secured thereto and projecting therefrom, the outer ends of said shanks being formed with diverging friction members to receive a scraping blade between them and spaced blade guides carried by the outer end of one of said shanks, the outer ends of said shanks being formed with diverging friction members adapted to receive a scraping blade between them and spaced blade guides carried by the outer end of one of said shanks.
5. An implement of the character described including a grip, shanks secured thereto and projecting therefrom, the outer ends of said shanks being formed with diverging friction members to receive a scraping blade between them and spaced blade guides carried by the outer end of one of said shanks, said guides being adjustable toward or from each other.

In testimony whereof I have signed my name.

JOSEPH GRULLER.
